UNITED STATES PATENT OFFICE

148,948

DESIGN FOR A COMBINATION BAKING DISH, GRIDDLE, AND DUTCH OVEN

Clyde A. Ovenshire, Berkeley, Calif.

Application May 27, 1946, Serial No. 130,128

Term of patent 14 years

(Cl. D44—1)

To all whom it may concern:

Be it known that I, Clyde A. Ovenshire, a citizen of the United States and a resident of Berkeley, in the county of Alameda and State of California, have invented a new, original, and ornamental Design for a Combination Baking Dish, Griddle, and Dutch Oven, of which the following is a specification, reference being had to the accompanying drawing forming part thereof, in which:

I claim:

The ornamental design for a combination baking dish, griddle, and Dutch oven, as shown.

CLYDE A. OVENSHIRE.
